UNITED STATES PATENT OFFICE.

BRADFORD BORDEN, OF CLEVELAND, OHIO.

PIPE-THREADING MACHINE.

Application filed April 9, 1924. Serial No. 705,298.

The invention relates to improvements in pipe threading machines as described in the present specification and illustrated in the accompanying drawings that form a part of 5 the same.

The invention consists essentially of the novel construction and arrangement of parts whereby during the threading operation the dies are caused to recede and at the end of 10 the cut are automatically freed from engagement with the pipe.

The objects of the invention are to eliminate the use of a leader screw and the subsequent necessity of having to turn the machine back over the thread in order to disengage the same; to provide a machine in 15 which the dies are readily interchangeable; to furnish an improved formation of thread cutting teeth which cooperating with a die 20 guiding means facilitates starting of the teeth upon the work; to economize in time and labor in threading pipes, and generally to provide a pipe threading machine which 25 will be inexpensive to manufacture, durable and efficient.

The invention further contemplates a machine of this character which is so constructed as to prevent cuttings removed from the work by the teeth from clogging 30 the die holders or otherwise obstructing the proper functioning of the machine.

In the drawings, Figure 1 is a side elevation of a pipe threading machine constructed 35 in accordance with my invention;

Figure 2 is a top plan view of the same; Figure 3 is a detail sectional view on the line 3—3 of Fig. 2;

Figure 4 is a sectional detail view on the line 4—4 of Fig. 3;

Figure 5 is a group perspective view of 40 portion of the die holding means, guide post and a portion of one of the dies.

Figure 6 is a plan view of the frame on a reduced scale;

Figure 7 is an elevation of one of the guide posts showing a diestock adjusting means;

Figure 8 is a side elevation of a modified form of guide post, and

Figure 9 is a side elevation of a die to operate therewith.

Referring specifically to the drawings, wherein like reference characters have been used to denote similar parts throughout all views, a conventional work holding means 55 is illustrated comprising a circular body portion 1 having a central work receiving open-

ing and slidably carrying the work engaging members 2 the movement of which is controlled by cam connections with a ring 2^a operated by a handle 2^b. I provide this 60 body portion with a medial neck 3 which is insertable through the central opening 6 of a rotatable yoke or die stock support 5 which latter is retained upon said reduced portion 3 by means of a nut or ring 4. As 65 will be observed from a glance at Figures 1 and 3, the yoke 5, in addition to being rotatable about the neck 3, is capable of limited axial sliding movement thereon between the nut 4 and the body portion 1. The purpose of this construction, as will be more 70 fully understood hereinafter, is to admit of the cutting of a short initial thread which will be straight and untapered, to enable the die teeth to become properly started in the 75 work without the necessity of a leader screw.

The yoke 5, as seen in Fig. 6 is substantially square the corners thereof being provided with transverse openings 7 there-through adapted to snugly receive posts 8 80 which will be suitably retained therein. These posts form a means for slidably supporting a die stock or frame 9 they being adapted upon sliding movement of said frame to cooperate with the dies carried 85 thereby to control the movement of the same toward and from the work in a manner and for a purpose which will be presently apparent.

The die stock 9 is substantially square, the 90 corners thereof being provided with radially disposed bosses or enlargements 10 extending inwardly to define a central work receiving opening concentric with the yoke opening 6. Through these bosses 10 openings 11 are drilled or otherwise produced for loosely receiving the posts 8 upon which, as previously intimated, the diestock 9 is designed to slide. Each boss is longitudinally slotted throughout its length to define a 95 slideway 13 for the reception of a die 14, it being noted from Figs. 2 and 5 that the post receiving openings are exposed to the slideways 13, and that each die is provided with pins 14^a projecting from either side 100 for reception in key ways 13^a in the sides of their respective slideways. As shown in Fig. 5 the slideways 13 are undercut, over-hanging portions 13^b serving to prevent vertical displacement of the dies 14.

Coming now to the die controlling feature of the invention and referring especially to

Figs. 1 and 5 it will be seen that the posts 8 are of substantially cylindrical contour each being provided, however, with a flattened longitudinal face 15 having formed 5 therein a longitudinal diagonally disposed groove 16 terminating in a laterally directed curve 16^a. The posts 8 will be so positioned in the corner holes of the yoke as to present their flat faces 15 toward the slideways 13 when the die stock 9 is located thereon, it being noted from Fig. 4 that the same extend into the slideways to the extent 10 of the depth of the adjacent key way 13^a being thus designed to receive in their diagonal grooves 16 selected ones of the die pins 14^a which may be alined to slide thereinto preparatory to the slipping of the frame 15 upon the posts.

The form of die which it is considered 20 preferable to use is one of the double ended type, shown in Figs. 1, 2 and 3, consisting of two sets of teeth 14^b and 14^c spaced by a slot 14^d, the set 14^b which is the first set to come into contact with the work being 25 set slightly inwardly with respect to the set 14^c so that, upon rotation of the die carrying frame 9 with its supporting yoke 5, the pipe or other work will be properly gripped and a thread roughed out preparatory 30 to being properly cut by the second set of teeth 14^c.

Rotative movement will be imparted to the frame 9 and yoke 5 around the portion 35 3 as an axis by means of handles 17 insertable in sockets 18 of the frame, it being evident that such movement will through the co-action of the sets of die teeth with the work, cause the frame to slide upon the posts 8 in the direction of the yoke 5. This sliding 40 movement of the frame results in a gradual receding of the dies 14 from the work by reason of the cooperation of the die pins 14^a with the diagonal post grooves 16 the dies being completely withdrawn from the 45 work when the pins have located themselves in the laterally curved groove terminals 16^a. This gradual receding of the dies from the work as a thread is cut thereon assures a desirable tapering of the thread to cause the 50 proper binding of a nut thereon. As the distance from the sets of die teeth 14^b, 14^c, to each pin 14^a varies, it will be noted that the distance which the dies extend into the 55 pipe or work opening is determined by placing selected die pins 14^a in the post grooves 16. The number of sizes of work which may be threaded with one set of dies is, therefore, limited only by the number of pins 14^a 60 which may be conveniently placed on the dies, such of the pins as are not cooperating with a post groove being free to slide in the keyways 13^a.

In Figs. 8 and 9 a modified form of construction is illustrated, the posts 19 being here provided with diagonal ribs 19^a co-

operable with selected transverse edge grooves 20^a of dies 20.

As a means for retaining the die stock or frame 9 upon its guide posts 8 I employ the adjusting screw 21, best illustrated in Figures 1, 2 and 7, the same including a threaded shank 22 adapted to be screwed into a tapped aperture in one of the posts 8, a depending skirt 23 surrounding this shank co-operating with the upper surface of the frame 9 to constitute an adjustable stop therefor whereby the outward thrust of the diestock 9 may be regulated.

The advantage of this construction will be 80 obvious since by the setting of the screw 21 at predetermined points on the post the initial extent to which the dies 14 protrude into the work receiving opening of the die holder 9 may be controlled. Limiting of the 85 outward thrust of the die holding frame 9 prevents the grooves of the posts 8 from acting upon the die pins 14^a to insert the dies into the work receiving opening to the limit 90 of their movement. It will also be obvious that the screw 21 may be used to determine the length of thread to be cut by limiting the outward movement of the die holder, acting as a gauge in this respect and also in determining the initial bite of the dies 95 in various sizes of work. Graduations 24 are provided upon the screw receiving post 8 so that desired adjustments may be quickly and readily made. Removal of the screw 22 of course permits changing the relative 100 positions of the dies with respect to the work by sliding the same to bring other pins 14^a into registry with the post grooves 16.

From the foregoing description read in connection with the accompanying drawings 105 it is believed that the novel features of construction of my machine will be readily understood and appreciated by those skilled in the art.

The operation may be summarized as follows:

The pipe or other work to be threaded will be engaged in the work holder, the portion to be operated upon being projected through the yoke 5 and the die stock 9 in the usual manner. It is to be understood that the end of the work to be threaded will be so located as to be engaged by the teeth 14^b of the die member 14 when the die holding frame 9 is in elevated position. The inwardly tapered formation of this set of teeth in connection with the receding movement of the dies 14 greatly facilitates the starting of the 115 thread.

Rotary movement is imparted to the die stock 9 and yoke 5 by means of the handles 17 causing the teeth 14^b to bite into the pipe to form a roughened or starting surface thereon. Since, as will be remembered, the yoke 5 carrying the diestock 9 is capable of 120 limited axial sliding movement on the neck 125 130

3 (Fig. 3) the entire assembly will be caused to move downwardly thereon from the nut 4, to the body portion 1 of the work holding means. It will now be readily understood 5 that this initial operation has not caused the dies to start their receding movement, its purpose being to facilitate the starting of die portions 14^b upon the work. The necessity of so called "leader screws" usually 10 employed for this purpose is thus obviated.

Upon the completion of this initial operation, the yoke 5 now being at the limit of its downward movement with the die teeth well started upon the work, continued rotation 15 of the diestock 9 will cause the same to move downwardly, the dies 14 meanwhile gradually receding from the work by reason of their sliding connection with the grooves 16 of the posts 8. The teeth 14^c following 20 the teeth 14^b are adapted to accentuate the cut made by the teeth 14^b and produce a thread of desired size.

Continued rotation of the diestock results 25 in the pins 14^a being brought into cooperation with the grooves 16^a which causes acceleration of the recession of the dies 13 to completely disengage them from the work, and permit removal of the same from the machine without necessitating rotation of 30 the diestock 9 in the reverse direction as is true in pipe threading machines which include a leader screw. Obviously a plurality of dies for forming either right or left hand threads of varying pitch may be used.

35 Since the dies are projected well into the work receiving opening to engage the work, cuttings therefrom will be permitted to fall through the opening and will not accumulate in the vicinity of the bosses 10, and since 40 no leader screw is interposed between the plate 1 and the diestock 9 this disposition of the cuttings is unobjectionable.

I claim as my invention:

1. A pipe threading machine including a 45 die stock, a series of work engaging dies carried thereby, guide means for slidably mounting said die stock for movement parallel with the axis of the work, and said dies and guide means having portions slidably 50 inter-engaging each with the other, one of said portions being a groove extending obliquely with respect to the axis of the work whereby through co-action with said other portion to actuate the dies transversely with 55 respect to the axis of the work during the sliding movement of said die stock.

2. A pipe threading machine including a 60 die stock, a series of work engaging dies carried thereby, guide means for slidably mounting said die stock for movement parallel with the axis of the work, and said dies and guide means having portions slidably 65 inter-engaging each with the other, one of said portions having a groove extending obliquely with respect to the axis of the work

whereby through said other portion to effect a gradual receding of the dies from the work during the threading operation, and one end of said groove being directed transversely away from the axis of the work 70 whereby to effect a complete disengagement of the dies therefrom at the completion of the threading operation.

3. A pipe threading machine including a diestock, a series of work engaging dies carried thereby, a support, guide posts carried by said support for slidably mounting said diestock for movement parallel with the axis of the work and each of said posts having a longitudinal groove therein obliquely disposed with respect to the axis of the work, 75 and said dies having means for sliding engagement in said grooves during the sliding movement of said stock on said posts whereby the dies will be gradually receded from 80 the work for cutting a tapered thread thereon.

4. A pipe threading machine including a support, posts carried by said support, a die stock slidably carried by said posts, dies 90 radially arranged in said stock, and a groove and pin connection between said dies and posts, said groove extending obliquely with respect to the axis of the work whereby the dies will be receded therefrom when the die 95 stock is slid in one direction and actuated theretoward when the die stock is moved in the opposite direction, and said groove and pin connection constituting a means for removably retaining said dies in said die stock. 100

5. A pipe threading machine including a support, posts carried by said support and having flat faces, said faces having grooves running in the direction of the length of said posts and obliquely disposed with respect to the axis of the work, a die stock removably positioned upon and slidably carried by said posts, dies slidably arranged in said stock, said dies having pins extending from the sides thereof, and said post grooves being open at the ends of said posts for the selective reception of said pins. 105

6. A pipe threading machine including a support, posts carried by said support and parallel with the axis of the work, said posts having grooves inclined across the axes thereof and extending therealong, a die stock slidably carried by said posts, dies freely movable in said die stock, each die having a plurality of pins extending from the sides thereof, said post grooves being open at the ends of said posts whereby to receive selected pins of said dies for locating the work engaging die portions in a predetermined position according to the size of 115 work to be threaded. 120

7. A pipe threading machine including a die stock comprising a substantially square plate having a work receiving opening, bosses radiating from said work receiving 125 130

opening toward the corners of said plate, said bosses having longitudinal die receiving slots therein and transverse post receiving holes communicating with said slots, dies 5 slidably receivable in said slots and having pins projecting from the sides thereof, posts loosely receivable in said post holes for slidably mounting said die stock on a support, said posts having longitudinal grooves 10 therein and disposed obliquely with respect to the axis of the work, and said grooves having one end open for the reception of said die pins, the opposite ends of said grooves being turned laterally in a direction 15 away from the axis of the work.

8. In a pipe threading machine including a die stock, a series of work engaging dies carried thereby, guide means for slidably mounting said die stock for movement parallel with the axis of the work, said dies and 20 guide means having portions slidably inter-engaging each with the other and arranged to actuate the dies transversely with respect to the axis of the work during the 25 sliding movement of the die stock, and a gage means carried by said guide means and engaging said die stock for limiting movement of the same in a direction to project the dies toward the work.

9. A pipe threading machine including a die stock, a series of work engaging dies carried thereby, guide means for slidably mounting said die stock for movement parallel with the axis of the work, said dies and 35 guide means having portions slidably inter-engaging each with the other, one of said portions being a groove extending obliquely with respect to the axis of the work whereby through co-action with said other portion 40 to actuate the dies transversely with respect to the axis of the work during the sliding movement of said die stock, and gage means acting upon said die stock for retaining the same against displacement, and said gage 45 means being adjustable to limit movement of said die stock in a direction to project the dies toward the work.

10. A pipe threading machine including a support, posts carried by said support and 50 having flat faces, said faces having grooves running in the direction of the length of said posts and obliquely disposed with respect to the axis of the work, a die stock removably positioned upon and slidably carried by said 55 posts, dies slidably arranged in said stock, said dies having pins extending from the sides thereof, said post grooves being open at the ends of said posts for the selective reception of said pins, and gage means carried by one of said posts and acting upon said 60 die stock for retaining the same against dis-

placement, said gage means being adjustable to limit movement of said die stock in a direction to project the dies toward the work.

11. A pipe threading machine including 65 a die stock, a series of work engaging dies carried thereby, guide means for slidably mounting said die stock for movement parallel with the axis of the work, and said dies and guide means having portions slidably 70 inter-engaging each with the other, one of said portions being a groove extending obliquely with respect to the axis of the work whereby through said other portion to effect a gradual receding of the dies from the work 75 during the threading operation, one end of said groove being directed transversely away from the axis of the work whereby to effect a complete disengagement of the dies therefrom at the completion of the threading 80 operation, and gage means carried by said guide means for retaining said die stock against displacement, said gage means being adjustable to limit movement of said die 85 stock in a direction to project the dies toward the work.

12. A pipe threading machine including a base, a rotatable member carried by said base and capable of limited axial sliding movement thereon, a die stock, a series of 90 work engaging dies carried thereby, guide means for slidably mounting said die stock upon said member for movement parallel with the axis of the work, said dies and guide means having portions slidably inter-engaging each with the other and arranged 95 to actuate the dies to recede from the work during the relative sliding movement of said die stock with respect to said member, and gage means carried by said guide means and acting upon said die stock for retaining the same against displacement, said gage means being adjustable to limit movement of said die 100 stock in a direction to project the dies toward the work.

13. In a pipe threading machine, a die stock having means controlled by the axial movement of the die stock in one direction for progressively actuating the dies toward the work, a member with respect to which the die stock is movable in an axial direction, means for indicating the proper extent of movement of the die stock in the first mentioned direction of axial movement 110 to project the dies to the appropriate starting position for predetermined sizes of work, said indicating means comprising a fixed and a movable element, and one of said elements being said aforementioned member.

In testimony whereof I have signed this specification.

BRADFORD BORDEN.
